FASTENING MEANS FOR IRONER ROLL COVERS

Jack A. Skelton, Atlanta, Ga., assignor to Southern Mills, Inc., Atlanta, Ga., a corporation of Georgia

Application March 8, 1952, Serial No. 275,585

6 Claims. (Cl. 29—118)

1

My invention relates to ironer rolls for use in mangles and more particularly to an improved fastening means for securing the pad and pad cover to the ironer rolls.

The use of asbestos cloth as an ironer roll cover has introduced a definite problem in satisfactorily securing the cover to the roll, because the asbestos cloth cannot be easily removed if it is glued to the roll; and although several other methods have been proposed and numerous mechanical means devised, all of them have proved to be unsatisfactory both from the standpoint of results obtained and the complexity of installation.

It is therefore an object of my invention to provide a means by which an asbestos cover may be secured to an ironer roll satisfactorily.

Another object of my invention is to provide a means which will secure both the pad and pad cover to the ironer roll without the use of tools or lead cloth.

Still another object of my invention is to provide a means for fastening a pad cover to an ironer roll regardless of the type of material from which it is manufactured such as asbestos, cotton, etc.

A further object of my invention is to provide mechanical means of fastening a pad and pad cover to an ironer roll that is simple and inexpensive to manufacture and install, and whereby the pad is held securely in place without the necessity of gluing.

Other and further objects and advantages of my invention will become apparent from the following disclosure when taken in conjunction with the accompanying drawings in which like characters of reference designate corresponding parts throughout the several views, and wherein:

Fig. 1 is a perspective view of a device embodying my invention.

Fig. 2 is a perspective view showing the relative relationship of the parts at the start of installation.

Fig. 3 is an exploded perspective view.

Referring now in detail to the embodiment chosen for purpose of illustration, numeral 10 denotes a cylindrical iron roller found in conventional rotary ironers or mangles. The roll 10 is customarily mounted for axial rotation on shaft 10'. Threadably engaging the outer periphery of roll 10 are a plurality of studs 11 which are spaced along a plane parallel to shaft 10' to provide a means for attaching the remaining structure to the roll.

As shown in Fig. 3, a thin rectangular fastening bar 12, which corresponds in length and

curvature to roller 10, is provided along one of its longitudinal sides with a plurality of spaced lugs 13 which correspond in their spacing to the spacing of studs 11. Lugs 13 are made integrally with bar 12 and are provided with keyhole apertures 14 to selectively engage or disengage their respective studs 11 as illustrated in Fig. 2 and Fig. 3.

From Fig. 3, it can be seen that the flexible asbestos sheet cover 15 is provided with spaced slots 16 adjacent its leading end. Slots 16 are of such shape and spacing that lugs 13 may be inserted through these respective slots 16 so that cover 15 may be folded around and be retained by bar 12, as illustrated in Fig. 2. Padding material 17 is inserted between the cover 15 and roll 10, and cover 15 is wrapped around roll 10 and over pad 17 until the abutting ends of pad 17 are covered, sufficient overlap of cover 15 being allowed to permit spring retainer 18 which engages reinforced holes 19 in cover 17 to maintain the proper tension on cover 17 to prevent unwrapping. Reinforced holes 19 into which spring 18 is engaged are so positioned that the length of the arc between them, measured from the end of cover 15 in the direction of wrapping, is less than one-half the circumference of the roll, hence the spring 18 will tend to tighten the wrapping regardless of whether it is connected directly between the holes or made to pass around shaft 10' as shown in Fig. 1. Cover 17 is wrapped to correspond to the direction of rotation of the roll 10, indicated by arrows in Figs. 1 and 2, thereby tending to tighten the cover 17 while the roll 10 is in motion. From this, it is obvious that the keyhole slots 14 must be positioned with the smaller dimension toward the outer end of lugs 13 to hold lugs 13 in locking contact with studs 11.

It is to be remembered that while a specific number of studs 11, lugs 13 and slots 16 has been shown, the actual number is a matter of choice and dependent upon the length of roll 10.

From the foregoing description, it will be seen that the pad 17 and pad cover 15 are simultaneously affixed to the roll 10 in a simple yet effective manner which may be accomplished without the use of any tools. It will also be apparent that the type of material from which the pad cover 15 is made does not affect the fastening means.

It will be obvious to those skilled in the art that my invention provides a needed article of great convenience and usefulness, and that while I have illustrated and described my invention in a very practical embodiment thereof, various

changes and adaptations may be made without departing from the scope of my invention as defined in the appended claims.

I claim:

1. In combination, a rotary ironer roll, a stud on the periphery of said roll, a fastening bar, a lug projecting from said fastening bar, said lug being detachably engaged by said stud, a cover of sheet material having one end folded under and positioned between said roll and said fastening bar, said sheet material being provided with an aperture through which said lug extends, and padding material positioned about the periphery of said roll, said sheet material extending over said fastening bar and thence over said padding material and around said roll to cover said padding material.

2. In combination, a rotary ironer roll, a stud on the periphery of said roll, a fastening bar, a lug projecting from said fastening bar, said lug being provided with keyhole slot detachably engaged by said stud, a cover of sheet material having one end folded under and positioned between said roll and said fastening bar, said sheet material being provided with an aperture through which said lug extends, and padding material positioned about the periphery of said roll, said sheet material extending over said fastening bar and thence over said padding material and around said roll to cover said padding material.

3. In combination, a rotary ironer roll, a plurality of studs on the periphery of said roll, a fastening bar, a plurality of lugs projecting from said fastening bar, certain of said lugs being detachably engaged by said studs, a cover of sheet material having one end folded under and positioned between said roll and said fastening bar, said sheet material being provided with a plurality of apertures through which said lugs extend, and padding material positioned about the periphery of said roll, said sheet material extending over said fastening bar and thence over said padding material and around said roll to cover said padding material.

4. In combination, a rotary ironer roll, a plurality of studs projecting from the periphery of said roll, a fastening bar, a plurality of lugs projecting from said fastening bar, certain of said lugs being provided with slots detachably engaged by said studs, a cover of sheet material

having one end folded under and positioned between said roll and said fastening bar, said sheet material being provided with a plurality of apertures through which said lugs extend, and padding material positioned about the periphery of said roll, said sheet material extending over said fastening bar and thence over said padding material and around said roll to cover said padding material.

5. In combination, a rotary ironer roll, a plurality of studs mounted on the periphery of said roll, a fastening bar, a plurality of lugs projecting from one side of said fastening bar, certain of said lugs being provided with slots detachably engaged by said studs, a cover of sheet material having one end folded under and positioned between said roll and said fastening bar, said sheet material being provided with a plurality of apertures through which said lugs extend, and padding material positioned about the periphery of said roll, said sheet material extending over said fastening bar and thence over said padding material and around said roll to cover said padding material.

10 6. In combination, a rotary ironer roll, a plurality of studs mounted on the periphery of said roll, a fastening bar, a plurality of lugs projecting from one side of said fastening bar, certain of said lugs being provided with keyhole slots detachably engaged by said studs, a cover of sheet material having one end folded under and positioned between said roll and said fastening bar, said sheet material being provided with a plurality of apertures through which said lugs extend, and padding material positioned about the periphery of said roll, said sheet material extending over said fastening bar and thence over said padding material and around said roll to cover said padding material.

JACK A. SKELTON.
